UNITED STATES PATENT OFFICE.

WILLIAM G. KENDALL, OF NEWARK, NEW JERSEY, ASSIGNOR TO PARFUMERIE RIGAUD, INC., OF NEW YORK, N. Y., A CORPORATION OF NEW YORK.

COMPACT HOLDER.

Application filed December 10, 1925. Serial No. 74,486.

This invention relates to improvements in compact holders, that is, metal holders for toilet powder compacts and has for its object the provision of a compact holder of 5 the ordinary form and size which will be capable of holding three or four separate cakes or compacts of toilet powder or rouge in a small space. For this purpose, I have devised a novel construction for holding two 10 semi-circular cakes of compact powder on one side of the holder, so that if two such devices be used in one compact holder, the holder will contain four cakes of compact powder.

15 Further objects of the invention will be apparent from the specification and drawings in which—

Fig. 1 is a plan view of the underside of my improved holder.

20 Fig. 2 is a plan view of the partition member showing hinge, etc.

Fig. 3 is a plan view of my improved tray used in this form of holder.

25 Fig. 4 is a sectional view along the line 4—4 of Fig. 2, the tray being also shown.

Fig. 5 is a perspective view of the partition member before being applied to the tray.

30 Fig. 6 is a perspective view of the tray.

Fig. 7 is a sectional view showing the 35 prongs of the partition member extended on one side of the tray only.

Fig. 8 is an end view of the partition member showing the various flange members and prongs before they are laterally bent.

The tray A with the protuberances B integrally formed therein, has the perforations C on the bottom thereof adapted to receive the partition member D. The partition

40 member D has a hinge E and flange members F at right angles to the surface of the base thereof, and these flange member F rest upon the base of the tray A. The prongs G at the base of the partition are adapted to

45 pass through the perforations C of the tray and they can then be turned at right angles to the base of said partition member, to securely fasten the partition member D to the tray A. The flanges F may be bent to

50 one side of the partition member only, as shown in Fig. 7 or to both sides of the par-

tion member as shown in Fig. 4. The upper portion of the partition member D is of a semi-circular form and is adapted to overlay either one of the semi-circular cakes 55 of compact held in the tray A on each side of the partition member.

The entire compact holder is not illustrated in the drawing, but it is obvious that the tray holding the semi-circular cakes or 60 compacts can be secured in any well known manner to one of the many forms of compact holders now on the market. It is unnecessary to have a cover member for both 65 cakes of compact which will simultaneously cover both of them, as it is desirable to expose merely one of the cakes at a time and to keep the other covered when one cake is exposed.

Having fully described my invention, 70 what I claim is:—

1. In combination, a tray having a plurality of perforations in the bottom thereof, and a partition member comprising a base portion and a second portion hinged to said 75 base portion, said base portion having a plurality of prongs projecting through said tray and connecting said base portion to said tray.

2. In combination, a tray having a plurality of perforations in the bottom thereof, and a partition member comprising a base portion and a second portion hinged to said base portion, said base portion having a plurality of prongs projecting through said 85 tray and connecting said base portion to said tray, said base portion also having flanges located above and adjacent the bottom of said tray.

3. In combination, a tray having a plurality of perforations in the bottom thereof, and a partition member comprising a base portion and a second portion hinged to said base portion, said base portion having a plurality of prongs projecting through said 95 tray and connecting said base portion to said tray, said perforations being located substantially along the central line of said tray and said second portion being adapted to cover substantially half of said tray. 106

In testimony whereof I affix my signature.

WILLIAM G. KENDALL.
